UNITED STATES PATENT OFFICE.

FRANK HARVEY AND JOHN KANE, OF RENOVO, PENNSYLVANIA.

CAR-COUPING.

SPECIFICATION forming part of Letters Patent No. 443,916, dated December 30, 1890.

Application filed October 2, 1890. Serial No. 366,800. (No model.)

To all whom it may concern:

Be it known that we, FRANK HARVEY and JOHN KANE, citizens of the United States of America, residing at Renovo, in the county of Clinton and State of Pennsylvania, have invented certain new and useful Improvements in Car-Couplings; and we do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to improvements in car-couplings, the object thereof being to provide an improved construction of the coupling and draw-head embodying means for automatically securing the interlocking coupling-hooks closed; and it consists in the construction and combination of the parts, as will be hereinafter fully set forth, and particularly pointed out in the claims.

In the accompanying drawings, forming part of this specification, Figure 1 is a perspective view showing the interlocking hook open. Fig. 2 is a horizontal sectional view. Fig. 3 is a detail perspective view of the latch.

A refers to the coupling-head and draw-bar, and B the coupling-hook which is pivoted to one of the forwardly-projecting ends of the head by a pin *a*. This coupling-hook *B* is attached by a knuckle-joint, the outer central portion thereof having a vertical wall *b*, which abuts against the vertical portion *b'* of the draw-head, so as to limit the outward movement of the hook *B*, the limit of said outward movement being shown in dotted lines, Fig. 2, and in full lines, Fig. 1. The head and hook are provided with shoulders *c* and *c'*, which limit the inward movement of the coupling-hook, which movement is also limited by the locking-arm *C*, abutting against the wall of the draw-head, as shown, said draw-head being recessed to receive said locking-arm, the upper and lower walls of said recess extending across the central portion of the draw-head to the intersection of the opposite forwardly-projecting portion thereof. This locking-arm, which moves

snugly in said recess, prevents any play of the coupling-hook other than a horizontal pivotal movement upon the pin *a*. The end of the locking-arm *C* is reduced to form an inclined portion *C'*, and a recess *d* is formed in said locking-arm between the inclined end thereof and the projecting portion, within which the coupling-hook of the opposite coupling will partially lie when the couplings are in engagement with each other.

Immediately rear of the coupling-head a draw-bar is located and has formed thereon a stop *E*, having a vertical edge *e*, against which one side of the latch will abut, and the outer wall of this strip is rounded, so as not to retain foreign substances. Rear of the stop *E* the draw-bar is provided with a central wall *G*, to which is pivoted, by means of a pin *g*, the latch *F*, said latch having a bifurcated rear portion, the front end thereof having a beveled recess, as shown at *h*, under which the end *C'* of the coupling-hook will pass and raise the same automatically when the coupling-hook is moved from the position shown in dotted lines, Fig. 2, to that shown in full lines.

The coupling-hook can be raised when it is desired to uncouple the cars by the rod *I*, which passes through an opening in the coupling-head and engages with an eye *i* beneath said opening.

It will be obvious that a car-coupling constructed as shown and described will automatically interlock, and to uncouple the cars it will only be necessary to elevate the catch 85 by drawing upon the rod *I*.

I am aware that prior to my invention many improvements have been made upon twin jaw-couplers of the type known as the "Janney" coupler; but by the construction herein shown and described I avoid the employment of springs and have practically only two movable parts—viz., the coupling-hook and the catch—and the coupling-hook is so secured to the coupling-head that both its inward and outward movement will be limited.

I am also aware that prior to my invention a car-coupling having a gravity locking attachment adapted to be used in connection with the interlocking hooks, as shown in Pat-

ent No. 412,879, dated October 15, 1889, has been provided, and I do not claim such construction as my invention; but

What I do claim as my invention, and desire to secure by Letters Patent, is—

1. The combination, in a chambered draw-bar having a coupling-head formed integral therewith, the coupling-hook pivotally attached thereto, said coupling-hook having a locking-arm with the recesses *d*, beyond which said locking-arm is reduced, said reduced portion having its upper end beveled, a latch horizontally pivoted to a vertical wall formed integral with the draw-head, the front end of said latch being oppositely beveled on its under side from the end of the locking-arm, and means for elevating said latch, substantially as set forth.

2. The combination, in a car-coupling, of a draw and coupling head constructed substantially as shown and provided with a central flat vertical portion *G*, to which the latch *F*, having its rear end bifurcated, is pivoted, a

raised portion or stop *E*, having a straight inner face and rounded outer portion, the forward end of the latch extending beyond the stop, and a coupling-hook having an extended and oppositely-beveled portion which engages with the front end of the latch, substantially as set forth.

3. The combination, in a car-coupling, of a draw-head carrying within the same a horizontally-pivoted latch, the rear end of which is bifurcated and pivotally secured to the vertical web *G* of the draw-head, and a stop formed integral with the draw-head and provided with a straight wall, against which one side of the latch abuts, substantially as set forth.

In testimony whereof we affix our signatures in presence of two witnesses.

FRANK HARVEY.
JOHN KANE.
